UNITED STATES PATENT OFFICE.

WILLIAM H. REEVES, OF ST. LOUIS, MISSOURI.

PUMP.

Application filed November 12, 1923. Serial No. 674,230.

To all whom it may concern:

Be it known that I, WILLIAM H. REEVES, a citizen of the United States, residing at the city of St. Louis and State of Missouri, have invented a new and useful Pump, of which the following is a specification.

This invention relates to pumps of the type used for removing or handling returns, consisting chiefly of condensate and air, from steam heating systems and other vapor apparatus in which a vacuum is maintained.

One of the principal objects of the invention is to provide a pump in which the principal elements are arranged in a novel relationship and are operated in a novel manner with the result that the efficiency of the heating system is improved, higher efficiency in the performance of the pump work is obtained, and loss of heat from the condensate by radiation is lessened by quiet operation of the mechanism. These desirable results are obtained by providing means for the continuous and prompt removal of the condensate, and automatically controlling the continuous removal of air at the variable rates necessary for the maintenance of the desired vacuum in the system, and separating the condensate and air and handling the same with individual pumps of types best adapted to their respective duties. Each pump is operated at its most advantageous speed and both are connected to a common motor or other prime mover by a practically silent form of driving connection. In the pumps now usually used for this service the air in the cylinder or other form of vacuum compartment is in intimate contact with condensate or other relatively hot water used for sealing or hurling purposes. The inevitable result of this is that low volumetric efficiency is obtained in pumping the air, because the heated water evaporates rapidly from any substantial increase in vacuum and resultant decrease in temperature, the vapor occupying space in the suction or filling compartment of the pump and in proportion to the space so filled with steam reduces the quantity of air that can be taken in from the heating system.

With wet vacuum pumps in which the condensate and air are handled together as a mixture by one pump and the pump is steam actuated, it is feasible to use a com-

mercial vacuum governor for controlling the steam supply to the pump for automatically obtaining the graduated speed variation necessary to maintain constantly the desired vacuum in the heating system, providing the pump is large enough to handle all of the condensate plus some air even at their low rates of speed. But where a pump of this form is power driven and where automatic speed graduation for the maintenance of a uniform vacuum cannot be easily obtained, the pump must either run continuously at full speed or be operated intermittently by starting and stopping. Both plans of operation last mentioned involve a sacrifice, one in waste of power to drive the pump in heat lost by radiation from the condensate by storing it for important intervals of time; and the other in an efficiency loss in the heating system through a fluctuating vacuum and possibly by an accumulation of condensate in the return line.

In other forms of power or electrically operated outfits in which the condensate and air are handled satisfactorily by individual pumps and which operate at constant speeds, automatic control for starting and stopping the unit is undertaken; but little economy can result from automatic control for intermittent operation because two separate and distinct pumping conditions obtain. The control must be such that the unit will run when there is condensate to be removed or when the vacuum is at or below the desired minimum degree at which the governor may be set for a starting point with the result that the vacuum pump will operate unnecessarily at times because there is some condensate to pump; and likewise the condensate pump will operate unnecessarily at other times because the vacuum is low.

Also in motor driven reciprocating wet vacuum pumps it is difficult to accommodate the pump and motor speeds. The ratio is so high that ordinarily two speed reductions are needed and the drive is usually accomplished by a double set of spur gears, or one spur gear reduction and one reduction by a belt and pulley. Both of these reductions are seriously noisy in locations where noise is objectionable.

Another object of my invention is to overcome all of the difficulties and objections

above mentioned and others encountered in the use of the usual pumps and to obtain other objects and advantages, all of which will be apparent from the following description reference being made to the drawings, in which

Fig. 1 is a plan view illustrating one form of the present invention.

Fig. 2 is a side elevation thereof.

Fig. 3 is an end elevation with parts in section.

Fig. 4 is an enlarged vertical sectional view of the governor controlling the valve in the suction pipe between the vacuum pump and the hotwell.

Fig. 5 is a plan view of the invention showing the principal units thereof arranged in different relationship from the relationship in which they are shown in Figs. 1 and 2.

Fig. 6 is a plan view showing the principal units of the invention arranged in still another relationship.

In the preferred embodiment of the invention as illustrated in Figs. 1, 2 and 3 the principal elements are the hotwell 1, the centrifugal condensate pump 2, the reciprocating piston vacuum pump 3, the worm gear drive 4 and the motor 5, all supported upon a common bed plate 6. A flexible coupling 7 is provided for driving cooperating parts of the shafts 8, 9 and 10. The shaft 8 is from the motor to the worm gear drive 4, the shaft 9 is from the worm gear drive 4 to the centrifugal condensate pump 2, and the shaft 10 is from the worm gear drive 4 to the reciprocating piston vacuum pump 3. Just as the construction of the internal mechanism of the motor 5 is so well understood that no detailed illustration thereof is required, so also is the internal construction of the centrifugal condensate pump 2, the reciprocating piston vacuum pump 3 and the worm gear drive 4 so well understood that no detailed illustration thereof is needed.

The hotwell 1 receives the returns of condensate and air through an inlet opening 11 and for the condensate has an outlet passage 12 leading to the centrifugal condensate pump 2. An opening 13 through the top of the hotwell 1 constitutes an outlet for air and suction and is controlled by a float valve 14 movable to and from a seat 15 within the cage 16 to prevent the passage of water and the flooding of the vacuum pump which might otherwise occur when the apparatus is idle, or if the condensate pump should fail to remove the condensate fast enough to keep the water level in the hotwell 1 at a relatively low stage. A vacuum governor 17 controls the valve 18 in the air suction pipe 19 leading from the opening 13 (Fig. 3) to the vacuum pump 3. The space below the diaphragm 20 of the vacuum governor 17 is

connected by a pipe 21 with the air suction pipe 19 between the valve 18 and the outlet opening 13 from the hotwell 1. The governor 17 functions to regulate the rates of flow of air from the hotwell 1 to the vacuum pump 3 requisite for the maintenance of the desired vacuum at which the governor 17 may be set and at the same time permits the vacuum pump 3 to run continuously at uniform speed. This results in a saving of power approximately in proportion to the reduction in quantity of air handled below the maximum capacity of the pump 3.

The centrifugal condensate pump 2 may be of any preferred or well understood construction and will remove the condensate from the hotwell 1 and discharge the condensate through an outlet passage 22 leading to the boiler or other point of disposition. The capacity of the condensate pump 2 is governed by the head of water on the suction side in the hotwell 1 and while running continuously at uniform speed will automatically remove condensate from the hotwell 1 at the various rates of flow; for, as the rate of inflow increases, the water level will rise and increase the suction head on the pump 2, thus enabling the pump to handle more water; and, as the rate of inflow decreases the water level and suction head will likewise decrease.

While the assembly and relationship of parts above described may be deemed preferable, I do not restrict myself thereto since it is obvious that the assembly may be varied. For instance, as shown in Fig. 5, the motor 5 has a double driving shaft extension and is placed in the center of the group, the condensate pump 2 being directly connected to one end of the motor shaft 23 and the worm drive gear 4 having its shaft 24 directly connected to the other end of the motor shaft 23, while the vacuum pump shaft 25 is directly connected to the gear shaft 26 of the worm gear drive 4.

Or, the parts may be assembled as shown in Fig. 6 in which the condensate pump 2 having double shaft extension 27 is placed in the center of the group, one end of the pump shaft 27 being directly connected to the motor shaft 23 and the other end of the shaft 27 being directly connected to the worm shaft 24. In this arrangement the gear shaft 26 of the worm gear drive 4 is directly connected to the shaft 25 of the vacuum pump 3.

From the foregoing it will be seen that the invention constitutes a compact assembly in which the principal elements perform their duties in a highly efficient manner, overcoming all of the disadvantages and objections hereinbefore mentioned and acting automatically when in use. I do not restrict myself unessentially, but what I claim and desire to secure by Letters Patent is:—

1. A pumping unit comprising a driving element, a liquid pump, an air pump, and a worm gear drive having worm and gear shafts connected to said liquid and air pumps and to said driving element.
2. A pump unit comprising a hotwell having openings for the removal of condensate and air, a condensate pump, a pipe from the condensate removal opening of the hotwell 10 to the condensate pump, a vacuum pump, a pipe from the air removal opening of the hotwell to the vacuum pump, a vacuum governor having a valve in said last named pipe, a driving element for the governor connected with said last named pipe at a location between said valve and the hotwell, a driving mechanism, and a worm gear device operated by said driving mechanism and connected with the condensate and vacuum pumps.
3. A pumping unit comprising a driving element, a condensate pump, a vacuum pump, a hotwell in communication with each of said pumps, and a worm gear drive having worm and gear shafts connected to condensate and vacuum pumps and to said driving element.
4. A pumping unit comprising a driving element, a condensate pump, a vacuum pump, and a worm gear drive having the gear shaft connected to said vacuum pump, the driven end of the worm shaft connected to said condensate pump, and the driving end of the worm shaft connected to said driving element.
5. A pumping unit comprising a hotwell having openings for the admission of returns and for the removal of condensate and air, a condensate pump having an intake connected with the condensate outlet of the hotwell, a vacuum pump having an intake connected with the air outlet of the hotwell, a driving element, and a worm gear drive having worm and gear shafts connected to said condensate and vacuum pumps and to said driving element.
6. A pumping unit comprising a hotwell having openings for the admission of returns and for the removal of condensate and air, a centrifugal type of condensate pump having an intake connected with the condensate outlet of the hotwell, a vacuum pump having an intake connected with the air outlet of the hotwell, a vacuum governor 50 controlling said intake, a driving element, and a worm gear drive having gear and worm shafts connected with the condensate and vacuum pumps and with said driving element.
7. A pumping unit comprising a hotwell having openings for the admission of returns and for the removal of condensate and air, a condensate pump having an intake connected with the condensate opening 60 of the hotwell, a dry type of vacuum pump having an intake connected with the air outlet of the hotwell, means for preventing flow of water from the hotwell to the vacuum pump, a driving element, and a worm gear drive having worm and gear shafts 70 connected with the condensate and vacuum pumps and with said driving element.
8. A pumping unit comprising a hotwell with openings for the admission of returns and for the removal of condensate and air, a condensate pump having an inlet connected with the condensate outlet of the hotwell, a displacement piston type of vacuum pump having an inlet connected with the air outlet of the hotwell, automatic means for opening and closing communication between said hotwell and said vacuum pump, means for preventing flow of water from the hotwell to the vacuum pump, a driving element, and a worm gear drive 75 having worm and gear shafts connected to the condensate and vacuum pumps and to a driving element.
9. A pumping unit comprising a hotwell having openings for admission of returns and for the removal of condensate and air, a condensate pump having an intake connected with the condensate outlet of the hotwell, a vacuum pump having an intake connected to the air outlet of the hotwell, a driving mechanism, a worm gear drive having worm and gear shafts connected to the condensate and vacuum pumps and to said driving mechanism, a vacuum governor having a valve in the suction of the vacuum pump, a driving element for the governor connected with the vacuum at a location on the inlet side of the governor valve.
10. A pumping unit comprising a hotwell having openings for admission of returns and removal of condensate of air, a condensate pump having an intake connected with the condensate outlet of the hotwell, a vacuum pump having an intake connected with the air outlet of the hotwell, a driving element, a worm gear drive having worm and gear shafts connected to the condensate and vacuum pumps and to said driving element; and a liquid check valve consisting of a float, a seat and a cage located in the suction of the vacuum pump preventing flow of water from the hotwell to the vacuum pump.
11. A pumping unit comprising a hotwell having openings for admission of returns and for the removal of condensate and air, a condensate pump having an intake connected with the condensate outlet of the hotwell, a vacuum pump, an intake to the vacuum pump connected to the air outlet of the hotwell, a driving mechanism, a worm gear drive having worm and gear shafts connected to the condensate and vacuum pump shafts and to said driving mechanism, a vacuum governor having a valve in the 115 120 125 130

suction of the vacuum pump, a driving element for the governor connected with said intake to the vacuum pump at a point on the inlet side of the governor valve; and a water ⁵ check valve consisting of a float, a seat and a cage located in the suction of the vacuum pump preventing flow of water from the hotwell to the vacuum pump.

12. A pumping unit comprising a hotwell ¹⁰ having openings for the admission of returns and removal of condensate and air, a rotary type of condensate pump having an intake connected with the condensate outlet of the hotwell, a vacuum pump, an intake to the ¹⁵ vacuum pump connected with the air outlet of the hotwell, a motor, a worm gear drive having the driving end of the worm shaft connected to said motor, the driven end of the worm shaft having flexible connection ²⁰ with the condensate pump and the gear shaft having flexible connection with the vacuum pump, a vacuum governor having a valve in the suction of the vacuum pump, a driving element for the governor connected ²⁵ with said intake to the vacuum pump at a point on the inlet side of the governor valve; and a water check valve consisting of a float, a seat and a cage located in the suction of the vacuum pump preventing passage of water ³⁰ from the hotwell to the vacuum pump.

13. A pumping unit comprising a hotwell having openings for the admission of returns and for the removal of condensate and air, a condensate pump connected with the opening ³⁵ for the removal of the condensate from the hotwell, a vacuum pump having an intake connected with the opening for the removal of the air from the hotwell, worm gearing, a motor for driving the worm gearing, connections for operating the condensate pump from the worm gearing, and connections for operating the vacuum pump from the worm gearing.

14. A pumping unit comprising a hotwell ⁴⁵ having openings for the admission of returns and for the removal of condensate and air, a condensate pump having an intake connected with the opening for the removal of condensate from the hotwell, a vacuum pump ⁵⁰ having an intake connected with the opening for removing the air from the hotwell, a motor, a worm gear drive device operated by the motor, and independent shafts for operating the condensate pump and the ⁵⁵ vacuum pump from the worm gear drive device.

15. A pump unit comprising a condensate pump, a dry vacuum pump, a driving element, a worm gear drive with gear and ⁶⁰ worm shafts connected to the condensate and vacuum pumps and to said driving element, a vacuum governor having a valve in the section of the vacuum pump, and a driving element for the governor connected

with the vacuum at a location on the inlet ⁶⁵ side of the governor valve.

16. A pumping unit comprising a condensate pump, a vacuum pump, a driving element, a gear drive with driving and driven shafts connected to said driving ⁷⁰ element and to the condensate and vacuum pumps, and a vacuum governor having a valve in the suction of the vacuum pump, the driving element of the governor being connected with the vacuum at a location on ⁷⁵ the inlet side of the governor.

17. A pumping unit comprising a hotwell having openings for admission of returns and for the removal of condensate and air, a condensate pump having an intake connected with the condensate outlet of the hotwell, a vacuum pump having an intake connected to the air outlet of the hotwell, a driving element, a gear drive with driving and driven shafts connected to said driving ⁸⁰ element and to the condensate and vacuum pumps, and a vacuum governor having a valve in the suction of the vacuum pump, the driving element of the governor being connected with the vacuum at a location on ⁸⁵ the inlet side of the governor valve.

18. A pumping unit comprising a hotwell having openings for admission of returns and removal of condensate and air, a condensate pump having an intake connected ⁹⁰ with the condensate outlet of the hotwell, a vacuum pump having an intake connected with the air outlet of the hotwell, a prime mover, a gear drive comprising driving and driven shafts connected to said prime mover ⁹⁵ and to the condensate and vacuum pumps; and a liquid check valve consisting of a float, a seat and a cage located in the suction of the vacuum pump preventing passage of water from the hotwell to the vacuum ¹⁰⁰ pump.

19. A pumping unit comprising a hotwell having openings for admission of returns and for the removal of condensate and air, a condensate pump having an intake connected with the condensate outlet of the hotwell, a vacuum pump having an intake connected to the air outlet of the hotwell, a prime mover, a gear drive comprising driven and driving shafts connected to ¹¹⁰ said prime mover and to the condensate and vacuum pumps, a vacuum governor having a valve in the suction of the vacuum pump, the driving element of the governor being connected with the vacuum at a point on ¹¹⁵ the inlet side of the governor valve; and a water check valve consisting of a float, a seat and a cage located in the suction of the vacuum pump preventing passage of water from the hotwell to the vacuum ¹²⁰ pump.

WILLIAM H. REEVES.
